(57) **CLAIM**

The ornamental designs for the split horseshoe, as shown and described.

DESCRIPTION

FIG. 1 is a top, rear, left perspective view of a top of a split horseshoe, showing my new design.

FIG. 2 is a bottom, front, right perspective view thereof.

FIG. 3 is a top plan view thereof.

FIG. 4 is a front elevation view thereof.

FIG. 5 is a bottom plan view thereof.

FIG. 6 is a left side plan elevation view thereof.

FIG. 7 is a rear elevation view thereof; and,

FIG. 8 is a top, rear perspective view thereof.

In the drawings, the equal-length broken lines depict portions of the horseshoe that form no part of the claimed design. The dash-dot-dash broken lines define boundaries of the claim.
